US00D881967S

(12) **United States Design Patent** (10) **Patent No.:** **US D881,967 S**
(45) **Date of Patent:** **** Apr. 21, 2020**

(54) **CAMERA**

(71) Applicant: **Shen Zhen Shi Ju Hui Tao Jin Chu Kou Co., Ltd.**, Guangdong (CN)

(72) Inventor: **Changlin Zhang**, XinJiang (CN)

(**) Term: **15 Years**

(21) Appl. No.: **29/633,532**

(22) Filed: **Jan. 15, 2018**

(51) LOC (12) Cl. **16-01**

(52) U.S. Cl.

USPC **D16/203**

(57) **CLAIM**

The ornamental design for a camera, as shown and described.

DESCRIPTION

FIG. 1 is a front elevational view of a camera showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a perspective view thereof;

FIG. 8 is a second perspective view thereof;

FIG. 9 is a third perspective view thereof; and,

FIG. 10 is a fourth perspective view thereof.

The broken lines shown in the drawings depict portions of the camera that form no part of the claimed design.

1 Claim, 10 Drawing Sheets
